UNITED STATES PATENT OFFICE.

BARTOLOMÉ VERGARA, OF MEXICO, MEXICO.

REINFORCED CONCRETE CONSTRUCTION.

1,264,582.

Specification of Letters Patent. Patented Apr. 30, 1918.

Application filed October 16, 1916. Serial No. 125,854.

To all whom it may concern:

Be it known that I, BARTOLOMÉ VERGARA, citizen of the United Mexican States, residing at Mexico city, Federal District, Mexico, have invented certain new and useful Improvements in Reinforced Concrete Constructions, of which the following is a specification.

The present invention relates to reinforced concrete constructions, and more particularly to the joinder of the blocks, sections and similar individual building elements of reinforced concrete used in the construction of walls, roofs, staircases and other parts 15 of an edifice.

Heretofore, considerable difficulty has frequently been experienced in fastening together the ends of the metal reinforcing members embedded in the blocks, etc., in order 20 to connect the abutting ends of adjacent blocks, so that relatively weak joints often result, especially where the reinforcing members take the form of heavy iron bars or beams. It is to overcome this substantial 25 defect in the ordinary method of procedure that my invention has been devised, the essential feature of the invention being the construction of the reinforcements in such a way that their projecting ends can be read- 30 ily and quickly locked together with the aid of simple and inexpensive devices to produce an extremely strong, permanent connection therebetween.

In the accompanying drawing:

Figure 1 is a perspective view, showing one way in which the ends of the members of a four-piece joint may be connected.

Fig. 2 is a perspective view, showing a slight modification or development of the 40 arrangement illustrated in Fig. 1.

Fig. 3 is a perspective view showing the invention as applied to a two-piece joint.

Fig. 4 shows a modification or development of Fig. 3.

Fig. 5 shows the application of the joint depicted in Fig. 1 to the girders of a roof.

Fig. 6 shows the two-piece joint of Fig. 3 applied to the sections of a staircase construction.

Figs. 5 and 6 also show end views of a girder and a staircase section respectively.

Referring to Fig. 1, the invention is illustrated as applied to a joint formed at the meeting ends of four metal bars B, though 55 it is to be understood that the particular number of bars is an immaterial matter, the

bars being arranged in angular relation with respect to one another, and having their aforesaid meeting ends bent abruptly upward. Also, said bars are shown as of 60 square or rectangular section, so that the mutually-adjacent faces of their bent ends will fit flush against each other. The bars are retained in position by means of an apertured or skeleton link or links, Fig. 1 65 showing a single link A, which fits over and closely engages the up-turned bar ends.

In Fig. 2, the meeting ends of the bars are substantially T-shaped, that is to say, said bars are provided at their said ends with 70 vertical cross-pieces or heads, which give them the appearance specified, and they are engaged by upper and lower links A and C, through whose open central portions the terminals of the cross-pieces project and are 75 conformably engaged by the marginal walls of the angular openings. The confronting faces of the said cross-pieces are rounded in this form of the invention, so that an opening is produced therebetween as will be ap- 80 parent upon inspection of Fig. 2, through which opening a retaining pin or rivet (not shown) is preferably inserted to hold the links in place.

In the constructions just described, the 85 links A, A, C are represented as disengaged from the bar ends for clearness of illustration, although in Fig. 1 the link is indicated in dotted lines at a in its effective or engaged position, in which position it may be re- 90 tained in any suitable manner, as for instance by clenching the corners of the rod ends, or, as illustrated in Figs. 1, 3 and 4, by simply upsetting the outer corner or cor- 95 ners of one of said ends.

The joints depicted in Figs. 3 and 4 embody the same general principles as those represented in Figs. 1 and 2, with this difference that only two bars B are used instead of four, so that an elongated rectangular link A is employed in place of a square link. In the case of Fig. 4, however, a third bar C is driven between the up-turned ends of the bars, in a direction perpendicular to the link A and to the body portion of the 100 bars; and in such instance, the bar C may have a wedge-shaped head and the opposed faces of the up-bent bar ends may be bevelled or inclined, as shown.

Fig. 5 illustrates the application of the 110 joints shown in Figs. 1 and 2 to the construction of a roof with concrete girders

arranged at right angles to each other, each girder section P having one of the bars B embedded therein. These girder sections are all of the same height, and they meet in precisely the same way as the bars B in said Figs. 1 and 2. Their confronting ends are preferably cut away or beveled at an angle of about 45° , so as to permit them to closely interfit and also to provide a space or opening O, into which plaster cement may be poured to fill the joint and the said space or opening itself, as well as the interstices between the bar ends. The spaces between the girders may be filled by concrete plates, slabs or blocks, which may be laid therein in any desired manner.

In Fig. 6, there is represented a portion of one of the sides of the staircase, comprising two concrete sections P connected together by means of the joint illustrated in Fig. 3.

It is to be understood that the foregoing are merely examples of certain of the uses to which the improved joints may be put. Consequently, no limitation to such uses is contemplated, nor is it intended that the invention is restricted to the precise structural details shown and described, excepting in so far as imposed by its scope as claimed.

I claim as my invention:—

1. In a reinforced concrete construction, a plurality of separate concrete building elements arranged in angular relation, so that the ends of all of them confront a common point; reinforcing bars embedded in said building elements and projecting outward through the confronting ends thereof, the projecting ends of said bars being formed with vertical, T-shaped heads which are arranged in abutting relation to one another; a single skeleton link fitting over the upper portions of all of said heads; a single skeleton link fitting over the lower portions of all of said heads, said links serving to hold

said heads in abutting relation; and retaining means whereby said heads and links are locked together.

2. In a reinforced concrete construction, a plurality of separate concrete building elements arranged in angular relation, so that the ends of all of them confront a common point; reinforcing bars embedded in said building elements and projecting outward through the confronting ends thereof, the projecting ends of said bars being formed with vertical, T-shaped heads which are arranged in abutting relation to one another; a single skeleton link fitting over the upper portions of all of said heads; a single skeleton link fitting over the lower portions of all of said heads, said links serving to hold said heads in abutting relation; and a retaining member driven between said heads to lock the same to said links.

3. In a reinforced concrete construction, a plurality of separate concrete slabs arranged to form a joint; reinforcing bars embedded in all of said slabs and projecting outward through the joining surfaces of said slabs, the projecting ends of said bars having abrupt, lateral extensions arranged in direct juxtaposition to each other; and a single link which is fitted over all of said extensions and by which they are locked together.

4. In a reinforced concrete roof or floor construction, sectional longitudinal and transverse concrete girders, having reinforcing bars embedded in their bottoms, the ends of all of said bars projecting outward from the joining ends of said girders and having abrupt, lateral extensions and a single link fitted over all of said extensions to lock them together.

In testimony whereof I have affixed my signature.

BARTOLOMÉ VERGARA.
